UNITED STATES PATENT OFFICE.

CHARLES L. LUNDSTEDT, OF LYNN, MASSACHUSETTS.

PERMUTATION-LOCK.

1,357,716.

Specification of Letters Patent.

Patented Nov. 2, 1920.

Application filed August 25, 1919. Serial No. 319,739.

To all whom it may concern:

Be it known that I, CHARLES L. LUNDSTEDT, a citizen of the United States, residing at Lynn, county of Essex, Commonwealth of Massachusetts, have invented certain new and useful Improvements in Permutation-Locks, of which the following is a specification.

This invention relates to permutation locks, and is particularly designed for application to the doors of club and lodge rooms or the like, where entrance is denied unauthorized persons but permitted the club members. The usual locks for this purpose are of the familiar key type and each club member is furnished with a key. It frequently happens, however, that the keys are lost or misplaced, with resultant inconvenience to the club member, and, moreover, the keys represent a considerable item of expense, especially where the membership is large.

To the end therefore of providing a simple and effective lock of the permutation type which will overcome these objections to the ordinary key lock, I have devised my present invention. In it, I secure the advantages of the ordinary key lock but avoid the objection as to the use of keys, all in a construction which is at once simple and reliable.

The construction and operation of my lock, together with an embodiment which well illustrates the principles involved, is disclosed in the accompanying specification and drawings, throughout which like reference characters are correspondingly employed. In the drawings:

Figure I is a face view of a lock in accordance with my invention applied to a door and as seen from the outside.

Fig. II is an edge view thereof.

Fig. III is a plan view of the lock casing with cover plate removed and showing the parts in their unlocked position.

Figs. IV, V, VI, VII and VIII are similar details illustrating the several positions of the locking elements.

Figs. IX, X, XI, and XII are details of the night latch mechanism, Fig. XI being a section on the line XI—XI of Fig. IX.

Fig. XIII is a transverse section through the lock casing, and

Figs. XIV, XV, XVI, and XVII are details of the permutation elements.

In Figs. I and II I have shown my lock

as applied to a door 1, which is suitably mortised, as indicated in these figures, to receive the locking parts, and is provided with the usual face plates 2, 3 and 4, which surround the mortise and afford guide and bearing for the locking bolt, spring latch and door knob and tumbler spindles.

Set within the mortise of the door is a two-part casing comprising a compartment-defining portion 5 and a removable cover portion 6 within which the locking parts are incased. The portion 5 may be conveniently sub-divided, as by the partition 24, and on one side of the partition is arranged the locking bolt and spring latch and the operating mechanism therefor, and on the opposite side of said partition is arranged the permutation tumbler mechanism and the finger-catch for the locking bolt.

Reciprocable within the casing by the door knobs 7 and 8, subject to the permutation feature and safety catch, is a locking bolt 9, the shank 10 of which is slotted longitudinally as indicated at 11 and laterally notched as indicated at 12, Fig. VII, and is guided on a toothed slide 13, which is similarly slotted and notched, as indicated at 14 and 15 respectively, Fig. V. The slide 13 is guided on a fixed guide pin 16 which projects through the registering slots 11 and 14, and the teeth of the slide 13 are indicated at 17.

Meshing with the rack teeth 17 is a pinion 18 on the end of a tumbler shaft 19 whereby to permit or prevent movement of the bolt according to the relation of the tumbler detents 37 on said shaft with respect to the slots of the tumbler wheels, A, A¹. As many tumblers may be provided as desired.

As here shown, each tumbler comprises a pair of complementary wheels A, A¹ which may be relatively adjusted to give any desired combination and which are connected to rotate together, as by the pins 29 on wheels A engaging in an annular series of holes 30 in wheels A¹. The wheels A are each provided with a peripheral series of slots 31 and the wheels A¹ with a single peripheral slot 32, and each pair of tumbler wheels is mounted upon an individual spindle 33 which is adapted to be rotated as by the thumb knobs 34 applied to opposite ends of the spindles over the faces of dials 35 on the inside and outside plates 3 and 4 of the door, the knobs 34 carrying pointers 36 which travel over said dials.

The tumblers may be set at any desired combination, and when this combination is registered, by rotating the several wheels in sequence, one of the notches 31 and the 5 notch 32 of each wheel pair will be alined with the tumbler detents 37 on the tumbler shaft 19, whereby to permit said shaft to rotate as the door knob is turned to move the bolt 9, and thus to permit the bolt 9 to 10 be moved.

The combination may be changed as often as desired, and in order to prevent the lock being picked by "feeling," one of the tumbler wheel pairs may be reversed as to the 15 others. The dials may be reproduced in reversed order upon the inside door plate 4 so that the combination may be worked from either side of the door, and the several tumbler wheels may be retained in the assembly 20 shown in the drawings as by the opposed blade springs 35¹.

The bolt 9 is advanced or retracted by operation of the door knob spindles 38 39. As here shown, one spindle 39 is threaded into 25 the opposite spindle 38. The spindle 38 carries a wing piece 40 adapted to coöperate with the tail piece 43 of a spring latch 44 which reciprocates within the casing 5 in a path parallel to that of the bolt 9, and the 30 spindle 39 carries sleeve 39¹ having a pair of spaced superposed pawls 41 and 42 of different lengths and set at different angles to each other. The pawl 42 is adapted, upon rotation of the spindle 39, to initially actuate the locking lever 20 for the bolt 9 and to subsequently actuate said bolt, and the pawl 41 is adapted to actuate the rack slide 13 substantially simultaneously with the actuation of the bolt by pawl 42.

40 The locking lever 20 overlies the bolt shank 10 and is pivoted on the guide pin 16. Said lever has a bayonet slot 21 into which extends a locking pin 22 fast on the bolt. Normally the pin 22 is disposed at 45 the inner end of the slot 21, as shown in Fig. III. Whenever the tumblers are properly positioned for the combination at which the lock is set (see Fig. IV) and the knob spindle 39 is turned, the shorter pawl 42 engages 50 the adjacent edge of the locking lever and swings said lever upon its pivot 16 to allow the locking pin 22 to clear the shoulder 21^a of the locking slot 21, and if the bolt be in condition to advance, said pin finally seats 55 at the outer end of the locking slot, whereby to lock the bolt in its projected position. After the locking lever 20 has been rocked on its pivot by pawl 42 to release the bolt, the further rotation of the spindle 39, moves 60 pawl 42 into notch 12 of bolt shank 10 and pawl 41 into notch 15 of rack slide 13 (see Fig. VII) whereby bolt and slide will be advanced as the spindle is turned, the advance of the slide being permitted by reason 65 of the registration of the tumbler notches

with the detents 37 which simply pass therethrough as the tumbler shaft 19 is rotated by engagement of the rack teeth 17 of the slide with pinion 18 of the tumbler shaft, and such action permitting advance of the 70 bolt. If the tumbler notches be not in registration with the detents 37, the slide 13 will be prevented from advancing and consequently the bolt will not advance. When fully projected, the bolt will be disposed in 75 substantially the position of Fig. IV. With the tumblers in proper position to permit, the bolt is retracted by rotating spindle 39 in reverse direction, the reverse of the action described in connection with the projection of the bolt taking place. In such reverse motion, the longer pawl 41 strikes the adjacent arm 45 of a forked operating lever, which is pivoted at 46, and has its opposite arm 47 disposed to strike an abutment 48 on the tail piece of the spring latch when said lever is swung upon its pivot by said pawl, whereby to retract the spring latch.

The locking lever is under spring control 80 as to its pivotal movement, as by the curved blade 23, which is anchored at one end to the locking lever and has its free end confined between said locking lever and the partition 24 of the casing. The spring for the 85 latch is indicated at 49, Fig. III, and normally tends to maintain the latch projected, and the latch is guided in its movements by a fixed guide pin 51 which projects through an elongated slot 52 formed in the shank 100 of the tail piece.

When turned to the position of Fig. VI, the pawl 40 on spindle 38 engages in a shallow notch 53 formed in the tail piece, and prevents projection of the latch. The locking bolt may be secured in its retracted position by a finger-operated catch exposed 105 when the door is unlocked through suitable openings in the face plate 2. As here shown, said catch comprises a pair of depressible buttons 25 which are connected to opposite ends of a centrally pivoted, spring backed lever 26 having pivoted thereto a locking pawl 27 adapted to be projected into a locking notch 28 formed in an adjacent edge of the bolt shank. See Fig. III.

As a supplement to the tumbler lock, I provide a dominant latch mechanism operative from the interior of the room only, and serving when set to physically lock the 120 outside knob spindle against rotation. As here shown, such mechanism comprises a pivoted dog 55 mounted in a kerfed block 56 set within the casing adjacent the knob spindle, and having a tail piece 57 provided 125 with a threaded socket 58 to receive a threaded stem 59 and with a locking pin 60 which normally lies within the kerf of the block as shown in Fig. XI.

By drawing outwardly upon the stem 59, 130

the tail piece of the dog is raised, throwing the hooked head of the dog into a locking recess 61 formed in the hub of the pawls 41, 42, see Fig. X, and the pin 60 withdrawn from the kerf of the block and may be seated on the upper face of the block straddling the kerf, as shown in Fig. IX, by a partial rotation of the threaded stem 59.

10 It will thus be seen that I provide a lock which combines the functions of the ordinary key-operated bolt and spring latch with a permutation feature dominating the bolt, but subject to the so-called "dominant latch" mechanism which is operable only from inside the room.

15 Various modifications in the construction and arrangement of parts may also obviously be made within the limits of the appended claims.

20 What I therefore claim and desire to secure by Letters Patent is:

1. A lock comprising a bolt, a slide, a tumbler shaft adapted to be rotated by said slide and having a detent, a tumbler having a slot adapted to be registered with said detent to permit movement of the bolt, and a spindle having a pair of pawls adapted upon rotation of the spindle to respectively engage the bolt and slide to advance or retract said elements when said tumbler slot is registered with said detent.

2. A lock comprising a bolt, a slide, a tumbler shaft adapted to be rotated by said slide and having a detent, a tumbler having a slot adapted to be registered with said detent to permit movement of the bolt, a locking lever normally disposed to prevent movement of the bolt, and a spindle having a pawl adapted upon rotation of the spindle to initially actuate said lever to release the bolt and to subsequently engage and move the bolt, and having a pawl adapted to engage and move the slide when said tubular slot is registered with the detent.

3. A lock comprising a slide, a bolt associated therewith, a tumbler shaft having a tumbler detent, an operative connection from said shaft to the slide, and a plurality of tumbler wheels comprising each a pair of superposed disks adapted to rotate as a unit but connected to each other for relative adjustment, one disk having a peripheral series of slots, and the other disk having a single peripheral slot, and said slots of the disk pair adapted to be registered with said tumbler detent to permit movement of the slide, and means moving the bolt upon registration of said slots.

4. In combination with a door having a mortise, a lock casing seated in said mortise, door knob and tumbler spindles entering said casing from opposite sides of the door, a bolt in said casing operable by rotation of the door knob spindles, tumbler

wheels in said casing controlling said bolt and operable by said tumbler spindles, a tumbler detent, a slide associated with said bolt and operatively connected with said detent, and means associated with said door knob spindles and adapted to advance or retract said bolt and slide when the tumbler wheels are properly positioned relative to said detent.

5. In combination with a door having a mortise, a lock casing seated in said mortise, door knob and tumbler spindles entering said casing from opposite sides of the door, a bolt in said casing operable by rotation of the door knob spindles, tumbler wheels in said casing controlling said bolt and operable by said tumbler spindles, a tumbler detent, and a dominant latch mechanism operable from the inside of the door independently of the tumblers to prevent movement of the bolt by manipulation of the tumblers from without the door.

6. In combination with a mortised door, a lock casing seated in said mortise, door knob spindles entering said casing from opposite sides of the door, a bolt in said casing operable by rotation of said spindles, a dominant latching mechanism for said bolt operable from the inside of the door, and comprising a pivoted dog, a bolt actuator on one of the door knob spindles adapted to be locked by said dog, and an operator for said dog arranged on the inner side of the door, and a permutation lock for said bolt subject to said latching mechanism.

7. In combination with a mortised door, a lock casing seated in said mortise, door knob spindles entering said casing from opposite sides of the door, a bolt in said casing operable by rotation of said spindles, a hub sleeved about one of said spindles and having a bolt actuating pawl and a locking slot, a dominant latch mechanism for said bolt comprising a dog pivoted for movement into and out of said slot of the bolt actuating pawl, an operator for said dog operable from inside the door, and a permutation lock for said bolt subject to said latch mechanism.

8. In combination with a mortised door, a lock casing seated in said mortise, door knob spindles entering said casing from opposite sides of the door, a bolt in said casing operable by rotation of said spindles, a hub sleeved about one of said spindles and having a bolt actuating pawl and a locking slot, a dominant latch mechanism for said bolt comprising a pivoted dog having a head movable into and out of said slot of the bolt actuating pawl and having a tail piece, an operator engaging said tail piece and operable from inside the door to rock said dog on its pivot, and a permutation lock for said bolt subject to said latch mechanism.

9. In combination with a mortised door, a

- lock casing seated in said mortise, door knob spindles entering said casing from opposite sides of the door, a bolt in said casing operable by rotation of said spindles, a spring latch mounted in said casing adjacent said bolt, a pawl mounted upon one of said spindles effective when swung in one direction to advance said bolt and when swung in the opposite direction to retract said spring latch, a dominant latching mechanism for said bolt, and a permutation lock for said bolt subject to said latching mechanism.
10. In combination with a mortised door, a lock casing seated in said mortise, door knob spindles entering said casing from opposite sides of the door, a bolt in said casing operable by rotation of said spindles, a spring latch mounted in said casing adjacent said bolt, a hub sleeved about one of said spindles and having a pawl effective when swung in one direction to project said bolt from the casing, a forked lever having an arm disposed for actuation by said pawl when swung in the opposite direction and having an arm disposed for engagement

with the spring latch to retract said latch, a dominant latching mechanism for said bolt and a permutation lock for said bolt subject to said latching mechanism.

11. In combination with a mortised door, a lock casing seated in said mortise, door knob spindles entering said casing from opposite sides of the door, a bolt in said casing operable by rotation of said spindles, a spring latch mounted in said casing adjacent said bolt, a pawl mounted upon one of said spindles and effective when swung in one direction to advance said bolt and when swung in the opposite direction to retract said spring latch, a dominant latching mechanism for said bolt comprising a dog pivoted for movement into latching engagement with said pawl, an operator for said dog operable from inside the door, and a permutation lock for said bolt subject to said latching mechanism.

In testimony whereof I affix my signature in presence of a witness.

CHARLES L. LUNDSTEDT.

Witness:

GEORGE B. RAWLINGS.
